J. B. DOLAN.
WINDOW BEAD FASTENER.
APPLICATION FILED MAY 1, 1911.

1,011,333.

Patented Dec. 12, 1911.

UNITED STATES PATENT OFFICE.

JOHN B. DOLAN, OF CENTRAL FALLS, RHODE ISLAND.

WINDOW-BEAD FASTENER.

1,011,333.

Specification of Letters Patent. Patented Dec. 12, 1911.

Application filed May 1, 1911. Serial No. 624,510.

To all whom it may concern:

Be it known that I, JOHN B. DOLAN, a citizen of the United States, residing at Central Falls, in the county of Providence and State of Rhode Island, have invented 5 certain new and useful Improvements in Window-Bead Fasteners, of which the following is a specification.

My invention relates to improvements in 10 attachments for window beads, and the purpose of my invention is to provide for an attachment for a window bead which will securely retain the bead in place, obviate the necessity of sawing the end of the bead on 15 a bevel, and be inexpensive to attach. I accomplish these objects by a device shown in the accompanying drawing, in which—

Figure 1 is a perspective of a portion of 20 an ordinary window sill having attached thereto a portion of a window jamb showing the spline in position. Fig. 2 is a plan of a window sill showing my attachment in position and a cross section of the window jamb. Fig. 3, a vertical view of the window jamb, 25 bead and attachment and a partial vertical section of the window sill, and Fig. 4, a detail perspective of my attachment.

The same parts are indicated by the same letters throughout the several views.

30 In all window beads in ordinary use the lower end is cut at a bevel to conform to the pitch or bevel of the window sill. As a result of this, each bead in process of manufacture has to be sawed twice at the lower 35 end—once to obtain the desired length, and again to cut the necessary bevel. By virtue of the beveled end, the bead cannot be reversed endwise, nor from front to back, as the bevel will fit only in one position.

40 Again, the ordinary window bead is constantly warping by reason of the exterior surface being exposed to the atmosphere and pulling out from its socket.

By the use of my device the window bead 45 may be reversed either endwise or from front to back and in case of sloping window sills the necessity of a double sawing, with the attendant waste of stock, is avoided, and the bead is held securely in position and cannot 50 move from its socket.

In Fig. 1, *b* is a portion of an ordinary window sill sloping in the manner in which window sills are ordinarily made; *d* is a portion of an upright window jamb, and *e* 55 a portion of a bead located therein, while *a* represents my attachment.

In Fig. 2, *d* is a cross section of the window jamb; *c* the channel into which the bead fits; *a* the bead, and *a*⁵ projecting prongs integral with the attachment *a* for the purpose of securing the attachment both to the window sill and to the bead. 60

Fig. 4 is a perspective in detail of my device; *a*³ being the upper surface thereof and *a*⁵—*a*⁵ prongs struck up from the body of *a*³ 65 by suitable means. It will be seen that the device *a*³ is wedge-shaped, that is, the back edge *a*² is thicker than the front edge *a*', so that *a*³ when in position upon the window sill, as in Fig. 1, will have its upper surface 70 horizontal. The relative size of the attachment *a*³ is such as to approximately equal the size of the cross section of the bead.

Fig. 3 shows my device in place ready for 75 the bead to be forced down upon it. In this figure, *c* represents the channel for the bead, *e* the bead itself; *e*' the lower end thereof and *a* my device in its place on the window sill with the prongs *a*⁵ driven into the window sill firmly, and another prong *a*⁵ projecting 80 upward ready to have the bead *e* forced down upon it, thus holding that securely in place also.

The exact number of projecting prongs, 85 *a*⁵, is not material, so long as some project upwardly and some project downwardly so as to secure the bead, and at the same time hold the device in place upon the window sill.

My device is made preferably of malleable metal so that the prongs *a*⁵ may readily 90 be struck up from the body, as shown in Fig. 4.

While in the great majority of cases the bead will be wedge-shaped because by far 95 the larger number of window sills are made sloping, as shown in the drawing, yet my device is equally applicable to a window sill which is horizontal. In that case, however, the device would be made of equal thickness throughout instead of wedge-shaped, as shown in the drawing.

Having now described my invention, what I claim and desire to secure by Letters Patent is:—

A window bead fastener comprising a 100 relatively narrow thin rectangular plate of a width to snugly fit the walls of the groove for the reception of the bead, said plate having one face flat throughout and against 105 which the lower end of the bead abuts, said plate having its lower face beveled through- 110

out to snugly fit against the sloping window sill, the bevel of said plate extending transversely with respect thereto, and said plate further having transversely extending 5 equally spaced portions struck therefrom to provide fastening prongs projecting in opposite directions with respect to each other and adapted to engage in the bead and sill whereby the plate is secured in position, the

area of said plate conforming to the cross 10 sectional area of the bead.

In testimony whereof I affix my signature in presence of two witnesses.

JOHN B. DOLAN.

Witnesses:

ROSCOE M. DEXTER,
EDITH M. BROMLEY.
